CLAIM

The ornamental design for a bluetooth earset case, as shown and described.

DESCRIPTION

FIG. 1 is a perspective view of a bluetooth earset case showing our new design;

FIG. 2 is a front view thereof;

FIG. 3 is a rear view thereof;

FIG. 4 is a left side view thereof where the right side view is a mirror image;

FIG. 5 is a top plan view thereof;

FIG. 6 is a bottom plan view thereof;

FIG. 7 is an exploded perspective view thereof; and,

FIG. 8 is a reference view thereof showing the state that the built-in charger terminal is drawn out.

The broken lines depict portions of the bluetooth earset case that form no part of the claimed design.
